US00D772261S

(12) **United States Design Patent** (10) **Patent No.:** **US D772,261 S**
Kothe et al. (45) **Date of Patent:** **** Nov. 22, 2016**

(54) **DISPLAY SCREEN WITH GRAPHICAL USER INTERFACE**

(71) Applicant: **Cognite, Inc.**, Austin, TX (US)

(72) Inventors: **Kyle W. Kothe**, Austin, TX (US); **Scott E. Goldberg**, Venice, CA (US); **John N. Faith**, Austin, TX (US)

(73) Assignee: **WayBlazer, Inc.**, Austin, TX (US)

(***) Term: **14 Years**

(21) Appl. No.: **29/511,681**

(22) Filed: **Dec. 12, 2014**

(51) **LOC (10) Cl.** **14-04**

(52) **U.S. Cl.**

USPC **D14/486**

(58) **Field of Classification Search**

USPC D14/485–488; D19/1–5; D20/10, 11, D20/22–38

(57) **CLAIM**

The ornamental design for a display screen with graphical user interface, as shown and described.

DESCRIPTION

The sole FIGURE is a front view of a display screen with graphical user interface showing the new design.

The outermost broken line rectangle illustrates a display screen or portion thereof and forms no part of the claimed design. The remaining broken lines illustrate a portion of the graphical user interface and form no part of the claimed design.
